UNITED STATES PATENT OFFICE.

MARGUERITE E. MOORE, OF NEW YORK, N. Y.

DESIGN FOR A STAKE RETAINER OR THE LIKE.

Application filed June 30, 1927. Serial No. 22,625. Term of patent 7 years.

To all whom it may concern:

Be it known that I, MARGUERITE E. MOORE, a citizen of the United States, and resident of the city of New York, in the county of New York, and State of New York, have invented a new, original, and ornamental Design for a Stake Retainer or the like, of which the following is a specification, reference being had to the accompanying drawing, forming part thereof.

The article is used for the reception of tokens in the course of amusement games.

Fig. 1 is a plan view, and Fig. 2 is a cross-sectional view, of a stake retainer.

I claim:

The ornamental design for a stake retainer or the like, as shown and described.

Signed at the city of New York, in the county of New York, and State of New York, this 28th day of June, A. D. 1927.

MARGUERITE E. MOORE.
